CAN PUNCHING AND SEALING MEANS

Adolf Swedeland, Denver, Colo.

Application December 5, 1933, Serial No. 701,075

2 Claims. (Cl. 230—51)

This invention relates to means for punching holes in the tops of cans so as to permit the removal of the liquids disposed in the cans.

An object of this invention is to provide a can 5 punching means which is exceedingly simple in construction and which embodies features whereby the device can be left on the can after a part of the material has been removed therefrom and the device will act as a sealing means to seal the 10 holes punched through by the punching members carried by the device.

Another object of this invention is to provide a device of this kind which includes means to permit the ready removal of the device from the top 15 of a can while not taking up a great amount of space so that the device can be left on a can and placed in a storage space and objects placed in the storage space relatively close to the can.

The above and various other objects and advantages of this invention will in part be described and in part be understood from the following detailed description of the present preferred embodiment, the same being illustrated in the accompanying drawing wherein:—

25 Figure 1 is a plan view of a device constructed according to the embodiment of this invention.

Figure 2 is a sectional view partly in detail taken on the line 2—2 of Figure 1, and showing the device before the points are forced through the top 30 of the can.

Figure 3 is a view similar to Figure 2 but showing the points projected through the top.

Figure 4 is a detail side elevation of the device partly turned so as to show the can piercing 35 members.

Figure 5 is a detail side elevation of the device with the top of the can shown in fragmentary form.

40 Referring to the drawing wherein like characters of reference designate corresponding parts throughout the several views, the letter C designates a can which is provided with a top T secured thereto in any desired manner. The can shown herein is shown merely diagrammatically 45 or as a matter of illustration to show the manner in which the device hereinafter described is applied.

In cans, particularly condensed milk cans, or the like, where it is desired to remove the milk 50 from the can, it is desirable that holes be made on opposite sides of the top so that the liquid can be poured through the holes in one side and air permitted to enter in the hole or holes on the opposite side.

55 In order, therefore, to provide a means whereby

the top T of the can may be pierced at desired points, I have provided a clamping member 10 in the form of a flat bar which is bent in the form of a segment and is of a length substantially greater than half a circle so that when the clamp 10 is disposed in the side wall of the can C, the clamp will firmly engage the side wall.

An upstanding arm 11 is integral with the clamp 10 and is disposed at a point inwardly from one free end of the clamp 10. This arm 11 projects 10 upwardly and terminates in an inwardly extending plate 12 which has one edge portion 13 there-of projecting beyond the peripheral portion of the can C. This projecting portion 13 provides a handle or grasping means whereby the device 15 may be lifted off of the can when desired. A can piercing member 14 is secured to the plate 12 and this can piercing member 14 is preferably of tapering construction terminating in a relatively sharp point so that the top of the can can 20 be readily pierced when the plate is pressed downwardly.

A second arm 15 is secured to or integral with the resilient clamp 10 and is disposed at a point spaced from the first arm 11 and is provided with 25 a horizontally disposed plate 16 extending inwardly over the top of the can T and provided with a pair of can piercing members 17 disposed in spaced relation to each other and positioned substantially diametrically opposite from the can 30 piercing member 14. These can piercing members 17 provide pouring openings in the top of the can whereas the single piercing member 14 provides an air hole in the top of the can. The plate 16 also has a projecting marginal portion 18 project- 35 ing beyond the periphery of the can C so as to facilitate the lifting of the device off of the top of the can and this projecting portion 18 coacts with the projecting portion 13 to permit the ready removal of the device from the can.

40 In the use of this device, the resilient clamping member 10 is initially disposed about the periphery of the can adjacent one end thereof and the two plates 12 and 16 are disposed in spaced relation to the top T of the can with the points of 45 the piercing members 14 and 17 confronting the top of the can. The plates 12 and 16 may then be pressed firmly toward the top T of the can, which action will cause the piercing members 14 and 17 to project through the top of the can. The device 50 can then be lifted off of the can by grasping the projecting edge portions 13 and 18 of the plates 12 and 16, respectively, and lifting the device upwardly. The can may then be tilted with the opening formed by the piercing member 14 upper- 55

most and the material poured out of the openings formed by the pair of piercing members 17.

Where it is desired to seal the openings formed in the top of the can, the device can be replaced 5 on the can and the piercing members 14 and 17 replaced in the original openings formed thereby and the can may then be placed in a suitable storage space and as the projecting portions 13 and 18 do not project unduly beyond the periphery of 10 the can, the device when used as a sealing means will not take up a great amount of space as would be the case where a projecting handle is provided.

It is, of course, understood that various changes 15 and modifications may be made in the details of construction and design of the above specifically described embodiment of this invention without departing from the spirit thereof, such changes and modifications being restricted only by the 20 scope of the following claims.

What is claimed is:—

1. A device as set forth comprising an elongated curved bar having a length substantially greater than a half circle, a pair of arms integral with 25 the bar and extending at right angles to the length of the bar, a plate integral with each arm and

extending at a right angle to each arm and disposed inwardly of the top of a can when in applied position, a can piercing member carried by each plate, and a projecting portion integral with each plate projecting beyond the circle defined by the bar and providing means to facilitate removal of the device from the top of a can.

2. A device as set forth comprising an elongated flat longitudinally curved bar substantially greater than a half circle, a pair of right angularly related arms integral with the bar and disposed in spaced relation to each other and positioned at a point intermediate each end of the bar, a relatively large plate integral with each arm and disposed at a right angle relative thereto, each plate having a portion thereof adapted to overlie the top of a can and another portion projecting beyond the periphery of the can, said other portion providing a releasing means to facilitate release of the device from a can, a piercing member carried by one of the plates, and a pair of piercing members carried by the other of the plates in spaced relation to each other and disposed diametrically opposed to said first piercing member.

ADOLF SWEDELAND.
